(57) **CLAIM**

The ornamental design for a physiological signal monitoring device as shown and described.

DESCRIPTION

FIG. 1 is a front perspective view of a physiological signal monitoring device;

FIG. 2 is a rear perspective view of the physiological signal monitoring device;

FIG. 3 is a front view of the physiological signal monitoring device;

FIG. 4 is a rear view of the physiological signal monitoring device;

FIG. 5 is a left side view of the physiological signal monitoring device;

FIG. 6 is a right side view of the physiological signal monitoring device;

FIG. 7 is a top view of the physiological signal monitoring device; and,

FIG. 8 is a bottom view of the physiological signal monitoring device.

The broken lines in the drawings depict portions of the physiological signal monitoring device that form no part of the claimed design.
